COMBINATION DENTIFRICE DISPENSER
AND TOOTHBRUSH HOLDER

Herbert Jacoby, Croton-on-Hudson, N. Y.

Application August 6, 1936, Serial No. 94,680

3 Claims. (Cl. 221—62)

The present invention relates to a combination dentifrice dispenser and toothbrush holder.

The primary object of the invention is to provide a toothbrush holder which will maintain the toothbrush in a sanitary condition when not in use and may also be associated with a specially constructed dispensing device attached to a dentifrice container whereby an even distribution of the dentifrice will be effected on the brush.

10 A further object of the invention is to provide a dispensing device comprising a valved trackway that may be removably attached to a container and adapted to receive the toothbrush holder and upon actuation of a slide valve the 15 dentifrice will be evenly distributed over the area of the brush.

The invention will be fully and comprehensively understood from a consideration of the following detailed description when read in connection with the accompanying drawing which forms 20 part of the application.

In the drawing:

Fig. 1 is a perspective view of the toothbrush holder detached from the dispensing device and 25 illustrating a toothbrush in phantom.

Fig. 2 is a perspective view of a dentifrice container and illustrating the dispensing device attached thereto.

30 Fig. 3 is a fragmentary sectional view illustrating the toothbrush holder associated with the dispensing device and receiving a quantity of the dentifrice; and

Fig. 4 is a sectional view taken on line 4—4 of Fig. 3 with the valve mechanism in closed position.

Referring to the drawing for a more detailed description thereof, the numeral 5 indicates a dentifrice container and, for purposes of illustration, said container is illustrated as being a 40 can, normally used for containing dentifrice powder, but it is to be understood that the dispenser may be used with collapsible tubes or other containers. The container 5 is provided with the usual restricted discharge outlet 6 to which the 45 dispensing device 7 is attached in any desired manner. The dispenser 7 is preferably channel shaped providing a trackway 8 for a purpose to be hereinafter described. A valve controlled slot 9 is provided in the central portion of the dispenser 7 and said opening is controlled by means of the spring actuated slide valve 10, which valve includes the spring 11 for normally retaining the valve in closed position. It is readily apparent 50 that pressure on the angle 12 moves the valve in-

wardly so as to align its opening 13 with the opening 9.

The dispenser 7 is especially constructed so as to be used in combination with a toothbrush holder of the form illustrated in Fig. 1 of the drawing. The toothbrush holder indicated generally by the numeral 14 includes a base 15 having a slot 16 corresponding to the slots 9 and 13. Extending upwardly from the base 15 are a pair of members 17 constructed preferably of a metal 10 that is readily flexible. The upper ends of the member 17 are bent in opposite directions to provide channels 18 adapted to receive the bristle supporting back 19 of a toothbrush 20, as clearly illustrated in Fig. 3 of the drawing. The member 17 is formed of flexible material so as to adapt the holder for various sized toothbrushes, it being readily understood that the members will expand or contract during the insertion of a toothbrush. If desired, the outer end 21 of the 20 holder 14 may be closed to aid in maintaining the supported toothbrush in a sanitary condition.

In the use of the herein described device, the holder 14 is normally disassociated from the dispenser 7 and supports therein toothbrush 20. 25 When desiring to use the toothbrush, the base 15 of the holder 14 slides within the channel 8 of the dispenser 7, at which time the container 5 is preferably in an inverted position. Actuation of the slide valve 10 aligns the openings, 9, 13 and 16, respectively, whereupon the dentifrice is applied to the bristles of the toothbrush in an even manner and without undue waste thereof. The toothbrush is then removed from its holder 14 and used in the usual manner for cleaning the teeth. After use the brush is placed within the holder 14 and said holder is then removed from the dispenser 7 and placed on a suitable supporting rack or the like.

40 From the above description it will be readily apparent that an individual holder may be furnished for each separate toothbrush and when used with the dispenser attached to the dentifrice container an even distribution of the dentifrice over the bristles of the toothbrush will be obtained without waste of the material.

45 It is to be understood that this improvement is capable of extended application and is not confined to the exact showing of the drawing nor to the precise construction described and, therefore, 50 such changes and modifications may be made therein as do not affect the spirit of the invention nor exceed the scope thereof as expressed in the appended claims.

What is claimed as new is:

1. In combination with a dentifrice container, dispensing means attached to said container, said means including a member having upturned flanged edges and a discharge slot therein, a holder for supporting a toothbrush, said holder including a base slidable in the flanged edges of the dispensing means.
- 5 2. In combination with a dentifrice container, dispensing means attached to said container, said means including a member having upturned flanged edges and a discharge slot therein, a valve slidably positioned adjacent said member, a holder for supporting a toothbrush, said holder having

a slotted base slidable in said flanged edges and flexible side portions having flanged edges for frictionally engaging the toothbrush head.

3. In combination with a dentifrice container, dispensing means attached to said container, 5 said means including a member having upturned flanged edges and a discharge slot therein, a holder for supporting a toothbrush, said holder having a slotted base slidable in said flanged edges, and slide valve means carried by said dispenser 10 for controlling discharge of the content of said container onto the toothbrush.

HERBERT JACOBY.
